UNITED STATES PATENT OFFICE.

HERBERT R. KEITHLEY, OF BUFFALO, NEW YORK.

CAR-TRUCK.

SPECIFICATION forming part of Letters Patent No. 658,448, dated September 25, 1900.

Application filed April 4, 1900. Serial No. 11,498. (No model.)

To all whom it may concern:

Be it known that I, HERBERT R. KEITHLEY, a citizen of the United States, residing at Buffalo, in the county of Erie and State of New

5 York, have invented new and useful Improvements in Car-Trucks, of which the following is a specification.

This invention relates to car-trucks having side frames which are constructed mainly of 10 pressed steel; and the objects of my invention are to provide an improved construction of the compression and tension members of the side frames which combines lightness and strength and to provide a strong and rigid 15 connection between the side frames and the transom.

In the accompanying drawings, Figure 1 is 20 a side elevation of a car-truck embodying my invention. Fig. 2 is an end view of the same, showing one half of the truck-frame in elevation and the other half in section, the plane of the sectional portion being in line 2 2, Fig. 1.

A is the upper or compression member, and 25 B the lower or tension member, of each side frame of the truck. The compression member of each side frame is composed of a flat horizontal top plate a , two vertical webs a' , extending downwardly from opposite edges 30 of said top plate, and horizontal flanges a^2 , projecting outwardly from the lower edges of said webs, as most clearly shown in Fig. 2. The tension member of each side frame is composed of a flat horizontal bottom plate b , 35 two vertical webs b' , extending upwardly from the edges of said plate, and horizontal flanges b^2 , projecting outwardly from the upper edges of said webs, as shown. Each of the compression and tension members is formed from 40 a single plate of pressed steel. The vertical webs of the tension and compression members are preferably constructed of greater depth at their central portion than at their end portions, as shown in Fig. 1.

45 C is the transom, which connects the side frames and which may consist of a box-girder of any suitable construction. The transom shown in the drawings consists of channel-bars having their flanges arranged to face outwardly and top and bottom plates c connecting said channel-bars. The tension and compression members A B are secured directly

to the transom by rivets or bolts d , which pass through the lateral flanges a^2 and b^2 of said members and through the top and bottom 55 plates of the transom.

The compression and tension members of each side frame are firmly secured together on opposite sides of the transom by heavy vertical bolts e and on opposite sides of the axle-boxes F by similar bolts g . These bolts pass through the top and bottom plates a b of the compression and tension members.

H represents vertical struts arranged between the compression and tension members 65 on opposite sides of the axle-boxes and having enlarged ends or heads h , which bear against the top and bottom plates a b of the side frames. These struts are secured in place by the bolts g ; which pass through the heads of 70 the struts.

I represents the usual spiral springs, which are interposed between the top plate of the compression member and the upper side of the axle-boxes and which are embraced on opposite sides by the vertical webs a' of said member. 75

The particular cross-sectional form of the compression and tension members herein shown and described is practically equivalent 80 to that of two Z-bars arranged face to face and bracing each other. This peculiar cross-section combines the greatest possible lateral strength and stiffness with a maximum vertical strength for a given metal section. 85

By riveting the lateral flanges a^2 and b^2 of the compression and tension members directly to the top and bottom plates of the transom a connection of maximum strength and stiffness is obtained between the transom and the 90 side frames of the truck, and with the additional strength contributed by the heavy connecting-bolts e and g and the struts H an efficient truck-frame is produced which combines the essential qualities of strength, stiffness, and lightness. 95

I claim as my invention—

1. A side frame for car-trucks having a tension member, and a compression member connected therewith and composed of a horizontal top plate and vertical webs extending downwardly from the edges of said plate and each provided at its lower edge with an outwardly-extending flange, said top plate, webs

and flanges being formed from a single piece of metal, substantially as set forth.

2. A side frame for car-trucks having a compression member, and a lower tension member connected therewith and composed of a horizontal bottom plate and vertical webs extending upwardly from the edges of said plate and each provided at its upper edge with an outwardly-extending flange, said bottom plate, webs and flanges being formed from a single piece of metal, substantially as set forth.

3. The combination with the side frame of a truck having a compression member composed of a horizontal top plate and vertical webs depending from the edges of said plate, and each provided at its lower edge with an outwardly-extending flange, and a tension mem-

ber composed of a horizontal plate and vertical webs extending upwardly from the edges of said plate and each provided at its upper edge with an outwardly-extending flange, of a transom having its end portion arranged between said compression and tension members and secured thereto by rivets or bolts passing through the top and bottom plates of the transom and the flanges of said compression and tension members, substantially as set forth.

Witness my hand this 29th day of March, 30
1900.

HERBERT R. KEITHLEY.
